CLAIM

The ornamental design for a correction roller, as shown and described.

DESCRIPTION

FIG. 1 is a top right perspective view of the correction roller (shown with the tip in broken lines) according to the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top right perspective view (shown with the tip tilted in broken lines) thereof.

The broken lines showing the tip of the correction roller serve the purpose of illustrative example and forms no part of the claimed design.
